UNITED STATES PATENT OFFICE.

JOHN E. DESMOND, OF DETROIT, MICHIGAN.

ENGINE-PRIMER.

1,322,674.

Specification of Letters Patent. Patented Nov. 25, 1919.

Application filed April 10, 1919. Serial No. 288,946.

To all whom it may concern:

Be it known that I, JOHN E. DESMOND, a citizen of the United States, residing at Detroit, in the county of Wayne and State 5 of Michigan, have invented a new and useful Engine-Primer, of which the following is a specification.

This invention relates to internal combustion engines, and is in the nature of an improvement upon the engine priming devices 10 disclosed in my copending applications Serial No. 233748 and Serial No. 271764.

In said priming devices there is employed a pump for inducing a flow of liquid fuel 15 through a suitable pipe to the intake manifold of the engine, said liquid fuel forming with the air in the manifold an explosive mixture which may be employed either for priming the engine or to momentarily enrich 20 the mixture delivered by the carburetor.

The present improvement has particular relation to the mounting of the pump and the construction of the piston thereof, and its objects are to facilitate assembly, to 25 permit a limited freedom of motion of the pump relative to its support in order to minimize the possibility of breakage, and to associate with the piston an improved valve for closing the discharge port of the pump 30 while the engine is running.

These objects are attained by the construction hereinafter described, and illustrated in the accompanying drawings, wherein,

Figure 1 is a view in side elevation and 35 partial section of the forward portion of a motor vehicle, showing the present invention applied thereto.

Fig. 2 is a view partly in section and partly in front elevation showing the mounting 40 of the pump with respect to the carburetor and intake manifold, and the provision for discharging the priming fluid within said manifold, the section being taken on line 2-2 of Fig. 1.

Fig. 3 is a longitudinal sectional view of 45 the pump.

Fig. 4 is a horizontal sectional view taken on line 4-4 of Fig. 3, and showing particularly the mounting of the pump and its delivery connection.

In these views the reference character 1 designates the body of a motor vehicle and 2 the engine thereof, the latter being supplied with an explosive mixture by a carburetor 3 55 through an intake manifold 4, and the carburetor deriving its liquid fuel supply

through a pipe 5 from a tank 6, as is common and well known in the art. Said pipe has its connection with the carburetor through a T fitting 7, the latter also connecting said pipe through a nipple 8 to the barrel 9 of the priming pump. The intake port 10 of the pump, with which port said nipple communicates, is preferably intermediate the ends of the barrel. The axis of 60 the barrel is situated in a vertical plane longitudinally parallel to the engine and is inclined upwardly from front to back at substantially a forty-five degree angle.

The barrel is mounted upon a bolt 10 70 transverse to the engine, said bolt engaging a lug 11 integrally formed upon the barrel exterior. The opening 12 of said lug receiving the bolt is slightly flared from its midpoint toward its ends so as to allow a slight 75 lateral angular movement of the barrel relative to its support, avoiding the possibility of breakage that might arise if the connection were rigid. The bolt 10 extends transversely to a bolt 13 and engages the head 80 thereof. The bolt 13, in addition to forming a support for the bolt 10, functions to clamp the intake manifold 4 to the carburetor 3. Into the lower end of the barrel 9 there is threaded the casing 14 containing 85 a spring-pressed ball check-valve 15 which normally closes a discharge port 16 in said casing for the priming charge. By means of a coupling 17 and a clamping nut 18, said valve casing is connected to a pipe 19 90 through which the priming charge may be conducted to the engine manifold 4. Preferably the priming charge is delivered to the manifold through a nozzle 20 located 95 interiorly of the manifold at the juncture of its branches and having the oppositely discharging outlets 21. Into the upper end of the barrel there is screw-threaded a plug 22 which is in turn rigidly engaged by a sleeve 23 extending upwardly and rearwardly in 100 alinement with the barrel 9 and terminally projecting through the dash 24. Said sleeve incloses the actuating stem 26 and is inwardly flanged at its upper end as indicated at 27 to guide said stem in its reciprocation. 105 The stem projects beyond the upper end of said sleeve and is terminally threaded to receive a handle or knob 28. Adjacent said knob the stem is further threaded for engagement by a pair of nuts 29 frictionally 110 interlocking and forming an adjustable stop to limit downward movement of the stem.

The piston 26 is hollow and has an interior web or partition 30 in its upper portion. The connection of the stem 25 to the piston is established by engaging a head 31, formed upon the lower end of said stem between the web 30 and a nut 32 screwed into the top of the piston. The head 31 is allowed a slight play between said partition and nut, and also the stem 25 is allowed some lateral play in passing through the central opening 33 of the nut. This avoids necessity for accurate axial alinement of the stem and piston, facilitates assembling, and minimizes the possibility of the piston binding, due to any slight bend in the stem. A plug 34 is inserted in the lower end of the piston and forms a mounting for a valve 35, which, when the pump piston is in its lower limiting position is adapted to close the outlet port 16. Said valve is tapered slightly at its lower end to facilitate engagement with its seat and is pressed downwardly by a coiled spring 36 engaged between its upper end and the web 30.

Considering now the operation and advantages of the above described construction, it is evident that the piston 26 is adapted not only to perform its normal function of ejecting a priming charge through the port 16, but is furthermore designed to function as a sealing valve for said port during normal operation of the engine, preventing any leakage through said port due to negative pressure in the engine manifold, and incidentally preventing the pipe 19 emptying itself into the manifold due to the same cause. That said additional function may be derived it is of course essential that the piston be returned always to its lowermost position after being reciprocated. It is not possible, however, to depend upon manual control of the piston for accurate seating of the valve 35, primarily for the two reasons that undue force would probably be used in seating said valve giving rise to rapid wear and consequent leakage, and that such an arrangement would require of the operator too much care and accuracy. By placing the nuts 29 upon the stem 25 to serve as a stop through engagement with the sleeve 23, the manually effected downward thrust of the piston is halted after the valve 35 has been engaged with its seat and the spring 36 has been placed under a slight compression. The spring pressed mounting of the valve 35 is advantageous in that the valve is cushioned in engaging its seat, in that a predetermined pressure is maintained upon the valve to hold it to its seat, and in that a

slight amount of variation is permissible as regards the position of the pump piston to effect engagement of the valve 35 with its seat. At low engine speeds the check valve 15 will remain seated and supplement the valve 35 in preventing leakage. At higher speeds of the engine the negative pressure may be sufficient to unseat the check-valve 15, and such pressure will then supplement the spring 36 in maintaining the valve 35 seated. The primary function of the check-valve 15 is to prevent the contents of the pipe 19 being drawn into the barrel of the pump on the upstroke of the piston. It is to be noted that in its raised position the piston is above the port 9^a so as to permit a charge of liquid fuel to enter the barrel beneath the piston through said port. The stem 25 has a certain amount of clearance within the plug 22 and sleeve 23, thus providing for the displacement of the liquid fuel from the barrel upon the upstroke of the piston.

The mounting of the pump barrel upon the bolt 10 is such as to allow turning of the pump upon the bolt about the axis of the latter and also a slight lateral swinging, this freedom of motion being desirable in view of the shocks and vibration arising from travel of the motor vehicle.

What I claim is:

1. In a device of the character described, the combination with a priming pump of a supporting member therefor and a bearing exteriorly carried by the pump within which said supporting member is engaged, the opening of said bearing member being flared to allow a play of the said member relative to the support.

2. In a device of the character described, the combination with a priming pump, a carbureter and an intake manifold, of a liquid fuel supply pipe, a supply connection from said pipe to the carbureter and pump respectively, and a bolt securing said carbureter to said manifold supporting the pump.

3. In a device of the character described, the combination with a priming pump, a carbureter and a manifold, of a bolt attaching the carbureter to the manifold, a second bolt transverse to the first mentioned bolt and attached to the head thereof, and a bearing member carried by said pump and engaged by said transverse bolt and interiorly flared to allow a limited swinging of the pump upon the supporting bolt.

In testimony whereof I sign this specification.

JOHN E. DESMOND.
